US0D1044022S

(12) **United States Design Patent** (10) **Patent No.:** **US D1,044,022 S**
(45) **Date of Patent:** **** Sep. 24, 2024**

(54) **DEVICE FOR COLLECTING AND TESTING
A FAECAL SAMPLE**

(71) Applicant: **HANGZHOU ALLTEST BIOTECH
CO., LTD**, Hangzhou (CN)

(72) Inventors: **Haipeng Hu**, Hangzhou (CN);
Cunbang Zheng, Hangzhou (CN);
Jiufa Lin, Hangzhou (CN); **Xiaojuan
Tu**, Hangzhou (CN); **Weike Lu**,
Hangzhou (CN); **Jinshu Chen**,
Hangzhou (CN); **Yinfei Wu**, Hangzhou
(CN); **Fei Gao**, Hangzhou (CN)

(73) Assignee: **HANGZHOU ALLTEST BIOTECH
CO., LTD**, Hangzhou (CN)

(**) Term: **15 Years**

(21) Appl. No.: **29/858,269**

(22) Filed: **Oct. 28, 2022**

(30) **Foreign Application Priority Data**

May 17, 2022 (CN) 202221192889.4

(51) **LOC (14) Cl.** **24-02**

Assistant Examiner — Kelly L Gross

(57) **CLAIM**

The ornamental design for a device for collecting and testing a faecal sample, as shown and described.

DESCRIPTION

FIG. 1 is a front, right and top perspective view of a device for collecting and testing a faecal sample showing our new design;

FIG. 2 is a rear, right and top perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view thereof.

The broken lines in the figures illustrate portions of the device for collecting and testing a faecal sample that form no part of the claimed design.

1 Claim, 8 Drawing Sheets
